ROTARY DICING MACHINE

Timothy F. Hornung, Oroville, Calif.

Application September 14, 1937, Serial No. 163,775

8 Claims. (Cl. 146—78)

My invention relates to improvements in a rotary dicing machine, and it consists of the combinations, constructions and arrangements hereinafter described and claimed.

5 The commercial food dicer first slices the material into flat slices and then these are fed one at a time onto a bed where the material is diced by a cutter, moved at right angles to the plane of the bed, and carrying a plurality of knives that cross each other for forming cutting dies that are square, rectangular or of any other desired shape. The dicing member reciprocates and this requires a definite amount of time for each stroke of the dicer and for the clearing 10 of the bed of the diced material, so that the bed will be ready to receive the next layer or slice of material.

The principal object of my invention is to provide a dicer that rotates rather than reciprocates. 20 The periphery of the rotary dicer is provided with intersecting knives that form dies of the desired shape. These dies have outer and inner ends that are open. The material to be diced is fed to the outer surface of the dicer and is diced upon being received in the outer ends of the dies. 25 The diced material is confined within the dies by a casing that encloses the periphery of the rotary cutter with the exception of the feed entrance to the cutter. It will be seen from this 30 that as the cutter rotates, the material that enters the dies on the cutter periphery, will make a complete revolution with the cutter and then will be forced into the interior of the cutter by the next layer of material which is being fed 35 into the cutter. Of course, the diced material may drop by gravity into the interior of the cutter or rotary dicer as it is carried over the top of the dicer and before it comes into contact with the next slice of material.

40 I provide novel means for expelling the material that drops or is forced from the dies into the interior of the cutter or dicer, and this means is formed from the spokes that support the periphery of the cutter. These spokes are arranged 45 in the shape of a spiral screw-ejector that will eject the diced material from one end of the cylindrical cutter or dicer.

The device in its simplest arrangement consists of a feed belt that will convey the slices of 50 material to the cutter or dicer, a rotary dicer which dices the material, and a belt or a table that will receive the diced material which is expelled by the ejector screw disposed within the cutter.

55 Other objects and advantages will appear in

the following specification, and the novel features of the device will be particularly pointed out in the appended claims.

My invention is illustrated in the accompanying drawings forming a part of this application, 5 in which

Figure 1 is a top plan view of the device;

Figure 2 is a side elevation;

Figure 3 is an end elevation;

Figure 4 is an end view of the rotary dicing 10 head;

Figure 5 is a horizontal section through Figure 4, portions of the rotary dicing head being shown in elevation;

Figure 6 is a section along the line 6—6 of Figure 15 5;

Figure 7 is a longitudinal section of a portion of the rotary dicer;

Figure 8 is an enlarged perspective view of a 20 portion of the dicing head periphery;

Figure 9 is a perspective view of the combined spokes and screw ejector for the diced material;

Figure 10 is a diagrammatic view illustrating the operation of the device;

Figures 11 and 12 are schematic views illustrating a step in the operation;

Figure 13 is a diagrammatic view similar to Figure 10, but showing the feed belt in a different position with respect to the dicing unit; and

Figure 14 shows a blank form from which a 30 cutting ring disc and spokes are formed.

In carrying out my invention, I provide a frame indicated generally at 1, and this frame carries guides 2 and 3 in which bearings 4 and 5 are slidably mounted. Adjusting screws 6 and 35 7 are connected to the bearings 4 and 5 respectively. The bearings 4 and 5 rotatably carry pulleys 8 and 9 and these in turn support a feed belt 10. The screws 6 and 7 may be adjusted for tightening the belt 10 to the desired extent 40 and for shifting the entire belt longitudinally with respect to the frame 1 for a purpose herein-after described.

The feed belt 10 may be actuated by any desired means and in Figures 1 and 2 I show a 45 motor 11 operatively connected to a reduction gear mechanism indicated generally at 12 by a belt and pulleys indicated generally at 13. A silent chain drive, generally indicated at 14 connects the reduction gear mechanism 12 with 50 the pulley 8 and in this way the belt 10 is moved so that its upper portion will move in the direction of the arrow 5 shown in Figure 1. The belt 10 conveys slabs or slices of the material, to be 55 diced, to a rotary dicer indicated generally at 15.

Before describing the rotary dicer in detail, it is best first to describe the frame structure that receives the dicer. This frame structure may be of any type desired and is shown consisting of four up-rights 16 that are supported by the frame 1 and in reality form a part of the frame. Semi-circular angle-iron members 17 are pivoted to two of the up-rights 16 at 18 and are removably secured to the other two up-rights 16 by any suitable fastening members indicated generally at 19. Each angle iron 17 carries a guide 20 for a bearing block 21. Each bearing block 21 carries guide pins 22, see Figures 2 and 5, and these are slidably received in a transverse member 23 carried by the guide 20. Coil springs 24 are mounted on the guide pins 22 and bear against the transverse member 23 and yieldingly urge the bearing blocks 21 downwardly. Nuts 25 are mounted on the guide pins 22 and may be adjusted for varying the compression of the springs 24. In this way the rotary dicer 15 may be yieldingly held against the belt 10 at the desired pressure.

The rotary dicer or cutter head is shown in Figures 4 to 9 inclusive. The dicer comprises a shaft 26 that is rotatably received in the bearing blocks 21, see Figure 5. On the shaft 26, I dispose a number of spacing members 27, see Figures 6 and 7. These members support the spokes 28 of ring-shaped cutter discs 29. Each cutter disc is identical and I have shown one of these in development in Figure 14.

The ring disc 29 has a portion 30 that extends diametrically across the ring and is provided with a central opening 31 for receiving the shaft 26. The portion 30 in reality forms two spokes 28 for the ring disc and these are shown in the shape of truncated triangles in Figure 14, although they may have parallel sides as shown in Figures 4, 6 and 9. The edges of the portion 30 are cut and bent along the dotted lines 32 for forming flanged sides to the spokes. The upper left and the lower right-hand flanges in Figure 14 are numbered 33 and are bent so as to extend at right angles to the portion 30 in one direction, while the upper right and lower left-hand flanges 34 are also bent at right-angles, but extend in the opposite direction.

These ring discs 29 are mounted on the shaft 26 and the spacing members 27 are provided with a length equal to the distance it is desired to space the ring discs 29 apart. The width of the flanges 33 and 34 is also equal to the length of the spacing members 27. When the ring discs are mounted on the shaft 26, they are rotated with respect to each other until the flanges 33 of all of the spokes abut the flanges 34 of adjacent spokes in the manner shown in Figures 6 and 9. This arrangement will form the spokes 28 into an ejecting screw for removing the diced material from the interior of the dicer 15.

It will further be noted that although the width of each spoke 28 may be the same throughout its length as shown in Figures 4, 6 and 9, or slightly triangular in shape, as shown in Figure 14, the flanges of the adjacent spokes will abut at their outer ends and will form a material ejecting screw in which the face of each step in the screw will be in the shape of a triangle with the base of the triangle disposed at the ring portion of the disc 29 and the apex of the triangle disposed adjacent to the periphery of the member 28. After the ring discs 29 have been assembled on the shaft 26 and are rotated so that the outer ends of adjacent flanges will abut

each other, the spokes 28 will take the positions shown in Figure 9, and may be locked in this position by nuts 35 screwed onto the shaft 26.

The peripheries of the ring discs 29 are sharpened so as to provide cutting edges 36, see Figure 5, and slits 37 are formed in the rings for receiving cross-knives 38, see Figure 8. The slits 37 are of a width equal to the thickness of the cross-knives 38 and may have a depth equal to one-half the width of the cross-knives. The cross-knives in turn are provided with slots 39, see Figure 8, of a thickness equal to the thickness of the discs 29 and a depth which may be equal to one-half the thickness of the knives 38. The figure shows how the cross-knives 38 are placed in the slots 37 and how the slots 39 receive the inner portions of the ring discs 29. It is obvious that the discs may have slots of a greater depth than the slots in the cross-knives if desired or vice versa.

In Figure 6, I show the flanges 33 lying in the same plane as the planes of the cutting knives 38 disposed adjacent to the outer ends of the flanges. In Figure 14 I illustrate the position occupied by the flanges 33 by the broken lines 33' and it will be noted that these lines are in direct alignment with two of the knife-receiving slits 37 provided in the ring portion 29. The flanges 33 and 34 of adjacent spokes abut each other at their outer ends as shown in Figure 6, and form a wedge whose apex is disposed at the ring 29. It is absolutely essential that this apex be disposed at the inner edge of a cutting knife 38 in order that material diced by the knife will not be impaled on the apex and thus prevent the proper functioning of the dicer, but instead will be guided into the interior of the dicer by the flanges 33 and 34. In this way the material will contact with the apex only at a point where it has already been cut.

An end disc 40, shown in Figure 5, acts as a closure for one end of the wheel or cutter 15 and is slotted to receive the knives 38. The knives carry small projections 41 that may be twisted into a slight angular position after the knives are assembled in place and this will lock the knives to the end disc 40. The opposite end of the wheel or cutter 15 is provided with a ring disc 42 and this disc carries a flange 43 that is bent so as to constitute a discharge lip for the diced material received within the cutter. Figure 8 shows the end disc 42 with the lip 43 removed in order to show this disc provided with slots 44 for receiving projections 45 on the cross-knives 38. These projectives are bent, as shown, for holding the knives in place. It will be noted that the slots in the end discs 40 and 42 do not extend to the peripheries. In this way the cross-knives are held against accidental removal. When it is desired to remove a cross-knife, the projections 41 and 45 are straightened and then the rim portions of the end discs 40 and 42 disposed adjacent to the knife ends are sprung outwardly a distance sufficient to free the projections 41 and 45 and this will permit the knife to be lifted out.

The dicing head as thus constructed is rotatably mounted in the bearing blocks 21 and these blocks in turn are slidably mounted in the guides 20. The U-shaped cover 17 is swung into closed position and the springs 24 will yieldingly urge the cutter down upon the belt 10 so as to frictionally engage therewith. The movement of the belt will impart a rotary movement to the 75

dicing head. The dicing head may be directly connected to the motor 11, if desired.

A guard 46 shown in Figures 2, 3 and 4 encloses the periphery of the cutter 15 with the exception of an entrance opening 47. This guard is composed of a top piece 46a and a sliding front section 46b and a sliding rear section 46c. The top 5 46a is carried by a frame 48, see Figure 2, which in turn is attached to the bearing blocks 21 by bolts 49 or other suitable fastening means. The frame 48 holds the top section 46a in a fixed position and concentric with the rotary cutting 10 unit 15.

The lower front section 46b is slidable in arcuate guides 50 carried by the top section 46a and this permits the front section 46b to be raised or lowered to vary the height of the slot 47 in accordance with the thickness of the material fed by the belt 10 into the cutter. The 15 rear section 46c of the guard slides over the top section 46a in arcuate channels 51 or other suitable guide means. The lower edge of the rear section 46c is placed near the belt 10 so that all of the material entering the cutter will pass 20 within the rear section 46c and will be held against radial movement in an outward direction while being carried through a complete revolution of the cutter. It will be seen that after the material makes one complete revolution with the 25 cutter, then the new material, being fed into the cutter, will force the diced material into the interior of the cutter.

Figure 5 clearly shows the interior of the cutter 15 as being hollow with the exception of the 30 spokes that are arranged in a spiral form for ejecting the diced material from the lip 43 as the cutter rotates. In Figure 3, I show a chute 52 extending from the annular lip 43 to a conveyor 35 53. Figures 1 and 3 show the conveyor 53 operatively connected to a shaft 54 by bevel gears 55. The shaft 54 extends from the reduction gear mechanism indicated generally at 12.

From the foregoing description of the various 40 parts of the device, the operation thereof may be readily understood.

Flat pieces of the material to be diced are placed upon the feed belt 10 and are delivered to the cutter 15. The thickness of the pieces placed upon the belt should not be greater than the 45 height of the cross-knives 38 and the ring portions of the discs 29. The movement of the belt will rotate the cutter and will feed the material to the periphery of the cutter. The cutter will enter the material and will dice it. This diced 50 material will be held against outward movement from the dies by the guard 46 and the diced material will either enter the interior of the cutter by gravity or will be forced into the interior after making one complete revolution with the cutter 55 55 by coming into contact with a new piece of material entering the dies of the cutter. After the diced material leaves the dies formed by the blades 29 and 38, it will be conveyed through the open end of the cylindrical cutter by the material 60 65 ejecting spokes 28 and will pass over the annular lip 43. From here the diced material will be conveyed to the belt 53 by the chute 52 and may then be sorted or conveyed to any desired mechanism.

70 It will be seen that the spacing of the slits 37 in the rims 29 determine one dimension of the material to be diced. The distance between the discs will determine the other dimension. It is possible to change the size of the diced material 75 and to make this material rectangular-shaped,

rather than square by removing certain cross-knives 38 as required. This will form rectangular dies with a length that is a multiple of the width. It is, of course, to be understood that some slicing device, not shown, will be used to preslice the material to the desired thickness before delivering it to the belt 10. The thickness of this material will provide the third dimension of the diced material. This permits the cutter 15 to produce diced material of uniform thickness.

The pitch of the screw ejector is determined by the number of spokes 28 and the width of these spokes at their outer ends. In designing a cutting unit the most suitable pitch can be selected. Figure 5 shows every other disc 29 provided with 15 spokes 28 and this permits small dicing to be accomplished without providing a multiplicity of spokes 28. Any desired number of discs 29, free of spokes 28, may be provided between discs that carry spokes.

Figure 2 shows the top of the belt 10 extending in a horizontal plane. It is possible to incline the belt as desired without affecting the operation of the device, providing the other parts of the device are brought into proper relative adjustment. The 20 primary requirement as to the relative position of the cutting unit with respect to the belt 10 is that the rims of the discs 29 (cutting edges 36) and the outer edges of the cross-knives 38 be in contact with the surface of the belt which conveys 25 the material to the cutter. The belt surface needs some support where it contacts with the cutter and this is provided by the pulley 8, see Figure 10. It is possible to cause the cutter 15 to contact with another portion of the belt and to support 30 this belt portion by rollers, or a fixed flat surface over which the belt would slide, or a large diameter drum disposed directly under the cutter. It is further possible to eliminate the belt and cause the cutter to ride directly on a roller, this 35 roller being lined with a resilient material.

Thus far nothing has been said as to the angle assumed by the cross-knives in the discs 29. It is possible to mount these cross-knives so that they will extend radially from the cutter axis. I 40 have found, however, that better cutting results are obtained if the knives are inclined from a radial position. In Figures 10, 11 and 12, I show diagrammatically the effect of inclining the cross-knives. The cross-knives 38 are placed in the 45 cutter 15 in Figure 10, so that an angle X is provided between the cross-knives 38 and radial lines extending from the cutter axis.

The angle X is a function of the radius R of the dicer 15, see Figure 10, the radius r of the 50 inner circle 15a to which the blade 38 is tangent, and the thickness T of the material 51. By changing all three of these dimensions or any one or two of them, a desirable angle X can be selected for the knife 38. In this way different shapes 55 of cubes can be produced. If the thickness T of the material 51 is such that the knife 38 will be at right angles to the belt 10 when entering the material, as shown by the knife 38a in Figure 10, then a diamond piece shown at 57a in Figure 11 60 65 will be cut. The leading and rear faces 57b and 57c of this piece will extend at an angle to the vertical line 56 which is approximately $\frac{1}{2}X$.

Now suppose a piece 58 is twice the thickness of the piece 57. The cross-knife 38 will have cut 70 half-way through the material by the time the knife reaches the position 38a in Figure 10. The effective angle through which the unit 15 has rotated during the cut will be twice the angle as required to cut through the piece 57. The knife 75

38 will therefore rotate about its cutting edge through an angle equal to $2X$. The cut produced by this knife in the material will be approximately at right-angles to the plane of the belt, since the point at which the knife enters the material will be almost directly above the point at which the knife leaves the material.

This actual condition is exaggerated in Figure 12 where the line $e-f$ forms an angle with a vertical line $e-g$ which represents the angular position of the knife 38 as it enters the material 58. The line $f-g$ will be the angle of the knife 38, as it leaves the material. The angles made by the knife as it enters and as it leaves the material are equal to the angle X and it will be seen that the curved line $e-g$ is the actual line of cut through the material. The angle of this cut is approximately one-half X . Since this curved cut is practically too small to be noticed, the effect will be that of a cube with sides $e-g$ at right-angles with the top and bottom of the cube.

Now if the conveyer belt assembly is moved to the right with respect to the cutter 15, in the manner shown in Figure 13, a different result will occur. The line of tangency between the cutter 15 and the pulley 8 will be at the point where a line 59 extending through the axes of the cutter and the pulley crosses the peripheries 30 of the two members. The moving of the pulley 8 to the right with respect to the cutter 15 will bring the support for the belt at a point nearer where the actual cut is commenced by the knife 38. In the arrangement of the parts as indicated in Figure 13, better results may be obtained in the cutting, because the beginning of the cut will be above the pulley 8. The angle of the cut made in the material will also be slightly changed.

40 In the actual cutting or dicing of the material it may happen that some materials will be compressed sufficiently during the cutting operation to remain in the dies formed by the discs and the cross-knives, and this material will be forced 45 out by the succeeding pieces of material entering the cutter. Still other materials may be so loosely received in the dies that they will require the guard 46 to retain the cut pieces in the dies until they drop into the interior of the cutter by gravity.

50 Referring to Figure 14, it will be noted that the diameter of the opening 31 is determined by the diameter of the shaft 26. The radius of the circle 15a is determined by the angle X selected. The diameter of the inner edge 29a of the ring 55 29 is determined by the depth of the disc rim selected. The outer diameter of the dicer is determined by the size of cube desired. The slits 37 must be of an even number in each ring 29 60 in order to have the slits disposed diametrically opposite each other. A slight change in either the size of the disc or the size of the cube may be necessary in order to have the parts properly positioned.

65 It is necessary that the disc blanks be laid out with the slits 37 arranged in this manner so that the spoke flanges will have their apexes meet on lines coinciding with the inner edges of cross-knives 38. It is also necessary to lay 70 the discs out in this manner in order to insure that the slits in succeeding discs when assembled, will be in line across the assembly. The number

of knives 38 disposed across the width of a spoke may be varied at will and will vary the pitch of the screw formed by the spokes.

While I have shown only the preferred form of my invention, it should be understood that various changes or modifications may be made within the scope of the appended claims without departing from the spirit of the invention. 5

I claim:

1. In a device of the type described, a hollow 10 cylindrical dicer formed from a plurality of cutting rings, spokes supporting the rings and arranged as a screw having a diameter equal to the inner diameter of the rings, said screw expelling the material from one end of the dicer. 15

2. In a device of the type described, a hollow cylindrical dicer formed from a plurality of cutting rings, spokes supporting the rings and arranged as a screw having a diameter equal to the inner diameter of the rings, said screw expelling the material from one end of the dicer, and cross-knives carried by the rings for forming dies that have open ends. 20

3. A dicer comprising a plurality of cutting rings arranged in parallel order and being spaced 25 from each other, a plurality of cross-knives carried by the rings and forming dies, and spokes supporting certain of the rings and being arranged to form a material ejecting screw within the dicer. 30

4. In a rotary dicer, a plurality of cutting rings, spokes for the rings and carrying flanges that interlock with each other, the outer ends of adjacent flanges contacting with each other for forming a material ejecting screw that has a 35 plurality of triangular steps.

5. A rotary dicer comprising a plurality of cutting rings revolvable about an axis, transverse cutters extending across the rings and cooperating therewith to form dies, certain of 40 said rings having supporting spokes, the spokes being arranged to form a material ejecting screw that has a diameter equal to the inner diameter of the rings. 45

6. A rotary dicer comprising a cylinder with 45 dies in its periphery opening into the interior of the cylinder, triangularly-shaped spokes supporting the cylinder and having their apexes in alignment with the walls of the dies, said spokes being arranged to form a screw that will eject 50 the material, received from the dies, from one end of the cylinder.

7. A rotary dicer comprising a cylinder formed from cutting rings and transverse knives that cooperate with the rings to form dies, certain 55 of the rings having supporting spokes with flanges that interlock with adjacent flanges for forming a material ejecting screw, the flanges forming triangles and the apexes being disposed in alignment with the walls of the dies. 60

8. In a rotary dicer, a plurality of cutting rings, having slots therein, cross knives received in the slots, spokes for certain of the rings and carrying flanges that interlock with each other, the outer ends of adjacent flanges contacting with each other for forming a material ejecting screw 65 that has a plurality of triangular steps, the apexes of the triangles being aligned with certain of said slots for guiding the diced material into the interior of the dicer.

TIMOTHY F. HORNUNG.
